9 Claims. (Cl. 66—20)

This invention comprises improvements in
knitted fabrics and in the method of producing
same. The invention refers to rib knitted fabric,
and has for its main object so to construct such
5 fabric that a finer gauge or closer rib can be ob-
tained than heretofore without appreciably im-
pairing or diminishing elasticity of the fabric.

The rib fabric according to this invention is of
the interlock type having the stitch wales of one
10 face directly over or imposed upon those of the
opposite face. As compared with the usual inter-
lock fabric, however, the improved fabric possesses
increased elasticity, a more uniform texture and
pleasing appearance and greater porosity.

15 In interlock fabric as heretofore produced the
stitches appertaining to successive stitch wales
are not in alignment across the fabric; in other
words, the successive stitches produced from one
20 thread lie at a different level from that of the
stitches produced from another thread, and con-
sequently also the stitch loops at one face of the
fabric are not accurately disposed directly over
the stitch loops at the opposite face.

Prior to this invention it has been the invariable
25 practice to produce interlock fabric by knitting one
course on alternate needles on each of two needle
rows or beds and then knitting the next course on
the remaining alternate needles of each of said rows
30 or beds and so on in alternation. The resultant
fabric consists of two ribbed webs with the needle
wales of one web disposed in the space between
the needle wales of the other web and having the
sinker bars of the two webs crossing; down the
35 wales the sinker bars of one web alternate with
the sinker bars of another bed in a 1 x 1 sequence.
In the fabric that is the result of the method and
machine according to the present invention the
sinker bars alternate in a sequence other than
40 a 1 x 1, desirably 2 x 2, and the invention com-
prises a method of producing a rib knitted fabric
consisting of two ribbed webs with the needle
wales of one web disposed in the spaces between
the needle wales of the other and having the
45 sinker bars of the two webs crossing in which a
plurality of successive courses of stitches are
formed on the same alternate needles of each of
two needle rows or beds, followed by a plurality
50 of courses of stitches formed on the remaining
needles of each of said rows or beds, and so
on in alternation.

The invention also includes a method of produc-
ing the improved fabric as above on a rib knitting
machine, said method comprising the following
cycle of operations, namely:— feeding thread to
55 and making stitches on alternate or selected

needles of each needle row or bed (the o
needles of one row being opposed to those
other row that are not so operated),
thread to and making further stitches
same needles of each row, feeding further
to and making stitches on the remaining
needles of each row and finally
thread to and making further stitches
last named needles.

This application is a division of Ser
78,326, filed May 7, 1936, now Patent No. 2,

For the purpose of more fully describ
nature of this invention reference will
made to the accompanying drawings, whi

Fig. 1 is a face view of a fabric constr
accordance with the present invention, th
loops on the rear face of the fabric being
smaller than those on the front face so
the purpose of giving a clear indication
construction.

Fig. 2 is a section on the fabric on the li
of Fig. 1.

Figs. 3, 4, 5 and 6 illustrate four successi
in the production of the fabric.

Fig. 7 is a plan view of cams for o
cylinder and dial needles in the productio
improved fabric.

In a convenient method of carrying out
vention a circular rib knitting machine
ployed having cylinder and dial needle
each containing two separately operated
needles, and the cylinder and dial needle
directly opposed or radially aligned as in
known machine for making interlock fab
vantageously each separately operated
needles in each needle row or bed is com
alternate needles, separate stitch cams fi
ing to operate the needles of each set in ei
lier in such a manner that when one set o
der needles is projected to take thread a
duce stitches, one set of dial needles is
taneously projected between said cylinder
and for this purpose the needles of one
each carrier are advantageously long nee
those of the other set short needles.

A preferred method of producing the i
fabric will now be described. At the first
long cylinder needles CN¹ and long dial
DN¹ are projected to take thread 1 and
by their respective cams CC¹ and DC¹
stitches, (Fig. 3). At the next or sec
the same needles i. e. the long cylinder
long dial needles DN¹, take another thre
are operated by the further cylinder &
cams CC², DC² to produce further stitch

4). At the third feed the short cylinder CN² and short dial needles DN² are projected and operated by cams CC³ and DC³ to take thread 3 and produce another course of stitches (Fig. 5), and at 5 the fourth feed the short cylinder CN² and short dial needles DN² are again operated by further cams CC⁴ and DC⁴ to take another thread 4 and produce a further stitch course, (Fig. 6). In this way it will be appreciated that two 10 successive courses of stitches are produced on the long cylinder and long dial needles followed by two successive courses on the short cylinder and short dial needles. In the customary type of interlock fabric sinker bars or loops passing from 15 front to rear of the fabric alternate with sinker bars or loops passing from rear to front in each sinker wale, consequently there is nothing to prevent the stitch loops produced from one thread at one knitted course from taking up a position out 20 of transverse alignment with stitch loops produced from another thread at the next preceding course, and the stitch loops on one face of the fabric, therefore, are not disposed directly over those at the other face and the fabric is rendered 25 less porous, i. e. less open. In the fabric according to the present invention, however, the formation of stitches on the same alternate needles of each set or row at two successive courses causes two successive sinker bars or loops in a wale to extend 30 in the same direction from one side of the fabric to the other between bars or loops extending in an opposite direction and in this manner the stitch rows are levelled up, i. e., transversely aligned, on both faces of the fabric and the 35 stitches at the front face of the finished fabric lie directly and accurately over the stitches at the opposite face.

We claim:-

1. A method of producing a rib-knitted fabric 40 consisting of two ribbed webs with the needle wales of one web disposed in the spaces between the needle wales of the other web and having the sinker bars of the two webs crossing, which method consists in forming a plurality of successive courses of stitches on the same alternate needles of each of two needle rows or beds, followed by a plurality of courses of stitches formed on the remaining needles of each of said rows or beds, and so on in alternation.
2. A method of producing interlock fabric, in 50 which two successive courses of stitches are formed on the same alternate needles of each of two needle rows or beds followed by two further successive courses of stitches formed on the remaining needles of each of said rows or beds, and so on in alternation.
3. A method of producing interlock fabric comprising the following repeating cycle of operations, namely:—feeding thread to and making stitches on alternate needles of each of two 60 needle rows or sets (the operated needles of one row being opposed to inoperative needles of the other row), feeding a second thread to and making further stitches on the same needles of each row, feeding a third thread and making stitches on the remaining (previously inoperative) needles of each row and finally feeding a fourth thread to and making stitches on the last named needles.

4. A method of knitting on two opposed banks of needles which comprises feeding thread to spaced needles in both banks and operating said needles to produce two rib courses, feeding thread to needles alternating with the first said needles and operating them to produce two rib courses oppositely disposed to the first two, and so on in alternation. 5

5. A method of knitting fabric on two opposed banks of needles the needles of one bank being 10 in alignment with the needles of the other, which comprises knitting a plurality of successive courses of a ribbed web on spaced needles of both banks, knitting a plurality of successive 15 courses of an oppositely ribbed web on spaced needles of both banks aligned with the first-said needles and so on in alternation.

6. A method of knitting fabric on two opposed banks of needles, which comprises knitting a plurality of successive courses of a ribbed web on 20 spaced needles of both beds of which needles those in one bank intercalate with those in the other bank while the other needles of said banks are inactive, knitting a plurality of successive 25 courses of an oppositely ribbed web on said other needles while the first mentioned needles are inactive, and so on in alternation, drawing the loops of the first course of a succession thereof in each web through the loops of the last course of the preceding succession in that web. 30

7. A method of knitting on two opposed banks of needles, which comprises knitting two successive courses of a rib web on odd needles in one bank and even needles in the other, knitting two successive courses of an oppositely ribbed 35 web on even needles in said one bank and odd needles in said other, and so on in alternation.

8. A knitting machine having two opposed banks of needles for drawing loops in opposite directions, thread-feeding means for feeding thread thereto, means for operating selected 40 spaced needles of both banks to produce a few ribbed courses of one ribbed web of which selected needles those in one bank alternate with those in the other bank, means for operating the remaining needles of said banks to produce a few oppositely ribbed courses of another ribbed web, and so on in alternation. 45

9. A method of knitting, on two opposed banks of needles, a rib-knitted fabric consisting of two opposed ribbed webs with the needle wales of one web disposed in the spaces between the needle wales of the other web and having sinker bars of the two webs crossing, which method consists in knitting a succession of series of ribbed courses, each of which series consists of a plurality of rib courses knitted on selected 50 spaced needles of both banks, of which selected needles those in one bank alternate with those in the other bank in a rib arrangement, and an equal number of opposed rib courses knitted on the remaining needles of both banks, and, in each series, knitting at least two of the first mentioned rib courses in direct succession to one another and also knitting at least two of the second mentioned rib courses in direct succession to one another. 55
